UNITED STATES PATENT OFFICE.

HENRY K. AUSTIN, OF READING, MASSACHUSETTS.

HEATING APPARATUS.

1,155,782.

Specification of Letters Patent.

Patented Oct. 5, 1915.

Application filed November 27, 1914. Serial No. 874,169.

To all whom it may concern:

Be it known that I, HENRY K. AUSTIN, a citizen of the United States, and resident of Reading, in the county of Middlesex and State of Massachusetts, have invented certain new and useful Improvements in Heating Apparatus, of which the following is a specification.

This invention relates to a furnace adapted to heat water either for the purpose of generating steam as a heating medium or of circulating hot water as a heating medium.

The invention has for its object to enable the fuel space of such furnace to be subdivided so that if desired only a part of it may be used for containing the burning fuel, the means for subdividing the fuel space constituting a water heating and circulating portion of the furnace.

The invention consists in the improvements which I will now proceed to describe and claim.

Of the accompanying drawings forming a part of this specification: Figure 1 represents a vertical section of a water heating and circulating furnace embodying my invention; Fig. 2 represents a section on line 2-2 of Fig. 1; Fig. 3 represents a section on line 3-3 of Fig. 1; Fig. 4 represents a perspective view of the partition which subdivides the fuel space, and a shield adapted to cover one of the subdivisions or fuel boxes.

The same reference characters indicate the same or similar parts in all the views.

In the drawings, 12 represents the grate and 13 the wall surrounding the usual fuel space of a water heating furnace, the wall 13 as here shown being hollow and constituting a water jacket which is suitably connected with the flow and return pipes of a house heating system.

14 represents a hollow vertical partition formed to subdivide the fuel space into two fuel boxes. The partition 14 is a thin box or water leg preferably formed to be inserted in the usual fuel-receiving opening covered by the usual firing door 15 above the fuel space, the height of the partition being such that its upper edge is preferably flush with, or somewhat below, the lower edge of said opening. The partition extends across the fuel space from front to rear in a plane midway between the ends of the door, so that each fuel box is uniformly re-

lated to the grate and door and is adapted to be charged with fuel through said door.

The lower portion of the partition 14 is provided with a return conduit member 16 adapted to be connected, as indicated by Fig. 1, with the lower portion of the hollow wall or water leg 13. The upper portion of the partition 14 is provided with a flow conduit member 17 adapted to be connected with one of the water or steam circulating spaces above the fuel space. Provision is therefore made for circulating water through the partition 14 so that said partition, which is in contact with incandescent fuel either at one or both sides, constitutes a part of a water heating and circulating system other parts of which are provided by said conduits. It is obvious that the partition 14 enables only one of said fuel boxes to be used in relatively mild weather, the other being left empty.

20 represents a shield which may cover the unused fuel box to prevent fuel from entering the same. Said shield is movable from one side of the fuel space to the other, and is supported at its inner edge by the partition 14 and at its outer edge by the fire box lining 21, inward edgewise displacement of the shield being prevented by suitable stops on the partition engaging the inner portion of the shield. Said stops may be provided by the flow conduit 17 and by a stud 22 on the upper edge of the partition, the shield having notches 23 to receive said conduit and stud, and a handle 25 by which it may be moved.

The sides of the partition may be strengthened by ribs 24 which increase the area of its heat-absorbing surface.

As here shown the partition 14 is formed as an independent piece or part and is detachably secured to the flow and return conduit members 17 and 16, which in turn are detachably secured to the furnace, so that provision is made for installing the partition in furnaces already constructed.

Having described my invention, I claim:

1. A furnace having a grate below and a firing door above the fuel containing space, a hollow vertical partition constituting a water leg extending across said space from front to rear above the grate and below the door in a plane midway between the ends of the door, said partition subdividing the fuel space into two fuel boxes uniformly related to the grate and to the door, and each adapted to be charged independently through the

- latter, and flow and return conduit members connected respectively with the upper and lower portions of the partition, the said conduit members and partition constituting 5 parts of a water circulating system.
2. A furnace having a grate below and a firing door above the fuel containing space, a hollow vertical partition constituting a water leg extending across said space from 10 front to rear above the grate and below the door in a plane midway between the ends of the door, said partition subdividing the fuel space into two fuel boxes uniformly related to the grate and to the door, and each adapt- 15 ed to be charged independently through the latter, and flow and return conduit members detachably connected respectively with the upper and lower portions of the partition and with the furnace, the partition 20 being formed as an independent part and detachably supported by said conduit members.
3. A furnace having a grate below and

a firing door above the fuel containing space, a hollow vertical partition constituting a water leg extending across said space from front to rear above the grate and below the door in a plane midway between the ends of the door, said partition subdividing the fuel space into two fuel boxes uniformly related to the grate and to the door, and each adapted to be charged independently through the latter, flow and return conduit members connected respectively with the upper and lower portions of the partition, and a movable shield adapted to cover either of said fuel boxes and expose the other, the partition being provided with stops to prevent inward edgewise displacement of the shield. 25 30 35 40

In testimony whereof I have affixed my signature, in presence of two witnesses.

HENRY K. AUSTIN.
